CLAIM

The ornamental design for a debris shield as shown and described.

DESCRIPTION

FIG. 1 is a top perspective view of a debris shield showing a first embodiment of our new design;

FIG. 2 is another top perspective view thereof with the disclaimed vacuum port plug and retainer cap and strap of the debris shield removed;

FIG. 3 a front elevational view thereof;

FIG. 4 is a right side elevational view thereof;

FIG. 5 rear elevational view thereof;

FIG. 6 is a left side elevational view thereof;

FIG. 7 is a top plan view thereof; and

FIG. 8 is a bottom plan view thereof.

FIG. 9 is a top perspective view of a debris shield showing a second embodiment of our new design;

FIG. 10 is another top perspective view thereof with the disclaimed vacuum port plug and retainer cap and strap of the debris shield removed;

FIG. 11 a front elevational view thereof;

FIG. 12 is a right side elevational view thereof;

FIG. 13 rear elevational view thereof;

FIG. 14 is a left side elevational view thereof;

FIG. 15 is a top plan view thereof; and,

FIG. 16 is a bottom plan view thereof.

The portions of the debris shield shown in broken lines form no part of the claimed design. Portions of the debris shield are shaded for transparency. The portions of the debris shield that are not shaded for transparency are not transparent. The

(Continued)

entire claimed debris shield shown in FIGS. 9-16 is transparent and shaded accordingly.
